UNITED STATES PATENT OFFICE.

GEORGE R. IRWIN, OF TURTLE CREEK, PENNSYLVANIA, ASSIGNOR TO WESTINGHOUSE ELECTRIC & MANUFACTURING COMPANY, A CORPORATION OF PENNSYLVANIA.

MOTOR-CONTROL SYSTEM.

1,416,032.

Specification of Letters Patent. Patented May 16, 1922.

Application filed December 12, 1920. Serial No. 430,158.

To all whom it may concern:

Be it known that I, GEORGE R. IRWIN, a citizen of the United States, and a resident of Turtle Creek, in the county of Allegheny and State of Pennsylvania, have invented a new and useful Improvement in Motor-Control Systems, of which the following is a specification.

My invention relates to motor-control systems and it has particular relation to systems of control for one-man cars.

One object of my invention is to provide a control system for a one-man car whereby a motorman will be compelled to alight from his car when it arrives at a railroad crossing; cross the tracks of the railroad and operate the car from a point from which he will have a clear view of the railroad tracks, as well as the street on which the car is operating.

For a better understanding of my invention, reference should be made to the accompanying drawings—

Figure 1 of which is a view, in side elevation, of a one-man car standing near a railroad crossing;

Fig. 2 is a schematic view of a stationary controller and of a trolley wire, which are shown in Fig. 1;

Fig. 3 is a view, in side elevation, of the face-plate of the controller shown in Fig. 1;

Fig. 4 is a diagrammatic view of the stationary controller shown in Figs. 1, 2 and 3 and of the associated circuits;

Fig. 5 is a sequence chart showing the order in which the line switch and the accelerating contactors shown in Fig. 4 close;

Fig. 6 is a schematic view of a motor-control system for a one-man car to which my invention may be applied.

Referring particularly to Fig. 1, a one-man car 1 operates upon a track 2. The car 1 has a trolley pole 3 to engage a trolley wire 4 which, in part, is duplex in form.

The car 1 is operated by a motorman 5, who is shown standing at a stationary controller 6, which is securely mounted upon a sidewalk adjacent to the curb 7 thereof.

A railroad crossing, comprising two tracks

8, is shown located between the car 1 and the stationary controller 6. The controller 6 is so located that the motorman 5 has an unobstructed view, in both directions, along the railroad tracks 8, as well as along the street upon which the car 1 is operated.

Referring to Fig. 2, the illustrated duplex portion of the trolley wire 4 comprises a pair of "dead" central portions 12 and 13, which are separated from the end portions, certain of which are "alive," as will be evident from the drawing, by means of a plurality of section breaks 9. A circuitous path 11 is provided to electrically connect the two energized main portions of the trolley wire 4. The section 12 of trolley wire 4 may be energized when a circuit is established through the stationary controller 6, as subsequently described in detail.

Referring to Fig. 6, a motor 16, having an armature 17 and a series field-magnet 18, is mounted upon the car 1 which it propels. The motor 16 is associated with a motor-control system comprising a circuit-breaker 19, a master controller 21 and a starting resistor 22. The controller 21 is provided with a handle 23 which may be removed therefrom.

The car 1 is provided with brakes which are operated by air that may be supplied from a reservoir (not shown), through pipes 24 and 25, to an electro-pneumatic valve 26. The electro-pneumatic valve 26 comprises a central chamber 27, an inlet chamber 28 and an outlet chamber 29, in accordance with standard practice. Valve plugs 31 and 32 control the supply of air from the inlet chamber 28 into the central chamber 27 and from the central chamber 27 to the outlet chamber 29, respectively. The valves 31 and 32 are mechanically connected by a shaft 33 which is actuated by an electromagnet 34. A pipe 35 delivers air from the central chamber 27 of the electro-pneumatic valve 26 to operate the brakes (not shown) of the car.

The valve plug 31 is maintained normally open and the valve plug 32 normally closed by means of a spring 36. Air pressure is continuously applied to the brakes unless the

electromagnet 34 is energized or unless the motorman maintains the handle 23 in its lower position to close a valve 37, which connects the pipe 24 to the pipe 25.

5 In Figs. 3 and 4, the stationary controller 6 is shown as having an "off" position and a plurality of operating positions *a*, *b*, *c* and *d*. A starting resistor 38 is associated with the stationary controller 6, and portions 10 thereof may be shunted by accelerating contactors 39, 41 and 42. A line switch or circuit-breaker 43 is provided for connecting the conductor 15 to the starting resistor 38.

The car 1 is ordinarily operated by the 15 motorman 5 actuating the master controller 21 by means of the handle 23. It is necessary for the doors of the car to be closed prior to the operation thereof, as one or more door-switches 44, which are connected, in series relation with a control circuit comprising the actuating coil of the circuit-breaker 19, are closed only when the doors assume their closed position.

When the controller 21 is actuated to position *a'*, a circuit is established from the trolley wire 4, through trolley pole 3, the actuating coil of line switch or circuit-breaker 19, resistor 45, contact segment 46 of master controller 21, door switch 44 and the actuating coil of electromagnet 34 of pneumatic valve 26, to ground.

The actuating coil of the electromagnet 34 being energized, inlet valve plug 31 will be closed and outlet valve plug 32 opened, 35 thereby removing the pressure from the car brakes.

The actuating coil of the circuit-breaker 19 being energized, the circuit-breaker will close, thereby establishing a circuit from the 40 trolley pole 3, through the co-operating contact members of circuit-breaker 19, drum segment 47 of master controller 21, starting resistor 22, armature 17 and series field-magnet winding 18 of the motor 16, to ground.

The motor 16 may be further accelerated by actuating the master controller 21 through the subsequent positions *b'*, *c'*, *d'* and *e'*.

50 For the sake of simplicity, the master controller 21 is shown in very simple form but it will be understood that my invention may readily be employed in conjunction with a more elaborate controller for governing a larger number of motors.

When the car 1 arrives near the railroad tracks 8, the trolley pole 3 will encounter the de-energized portion 12 of the trolley wire 4, thereby stopping the motor 16 and 60 causing air to be applied to the brakes. The car 1 is thus automatically stopped before reaching the railroad tracks 8. It will then be necessary for the motorman to remove the handle 23 on the controller 21, after he 65 has opened the doors of the car. The con-

troller 21 must be left in one of its operative positions.

The motorman is required to close the doors of the car 1 by placing the handle 23 upon a door-closing device 48 that is 70 situated on an outer wall of the car adjacent to the doors. By actuating the device 48 by means of the handle 23, the doors of the car are closed either mechanically or electrically, thereby closing the switch 44 which 75 is connected, in series relation, with the actuating coils of circuit-breaker 19 and of electromagnet 34.

The motorman 5 next crosses the railroad tracks 8 and, after ascertaining 80 whether it will be safe to operate the car 1 over the railroad crossing, he applies the handle 23 to the shaft of the stationary controller 6 and actuates the controller from its "off" position to position *a*.

A circuit is thereupon established from trolley wire 4 through conductors 11 and 14, resistor 49, contact segment 51 of master controller 6 and the actuating coil of line switch or circuit-breaker 43 to ground.

The circuit-breaker 43 being closed, a circuit is established from the trolley wire 4 through conductors 11 and 14, starting resistor 38, the co-operating contact members of circuit-breaker 43 and conductor 15 to the 95 de-energized portion 12 of the trolley wire. The section 12 now being energized, a circuit is established therefrom through the trolley pole 3, the master controller 21, starting resistor 22 and motor 16 to ground, 100 as has heretofore been described.

The brakes of the car will also be released, as the actuating coil of the electromagnet 34, which controls the pneumatic valve 26, is energized by a circuit which 105 has been previously described. The motorman may increase the speed of the car, by actuating the stationary controller 6 to positions *b*, *c* and *d*, which causes the accelerating contactors 42, 41 and 39 to successively 110 close, thereby shunting portions of the starting resistor 38.

When the car 1 has crossed the railroad tracks 8, the motorman returns the stationary controller 6 to its "off" position, thereby de-energizing the trolley-wire portion 12 and the motor 16. A "dead" trolley-wire extension 12^a may also be provided to prevent the motorman from operating the car 1 too great a distance beyond the place 120 where the master controller 6 is located.

After the car 1 has travelled beyond the crossing 8, the motorman opens the doors of the car by placing the handle 23 upon the mechanical device 48 and actuating it. Upon the doors of the car being opened, the switch 44 is opened, thereby preventing energization of the actuating coil of the circuit-breaker 19 and the actuating coil of the electromagnet 34.

- The motorman transfers the trolley pole 3 from the de-energized portion 12 or the portion 12^a of the trolley wire 4 to an adjacent "live" section of the trolley wire and 5 returns to the car. After closing the doors, he may operate the car in the usual manner. If, for any reason, the motorman should forget to open the doors before transferring the trolley pole from a de-energized trolley 10 wire portion to a "live" section of the trolley wire, he can stop the car by merely pulling the trolley pole 3 from the trolley wire 4, thereby de-energizing the motor 16 and setting the brakes.
- 15 It will be noted that material advantages obtain by employing the controller handle 23 for closing the car doors when the motorman is outside of the car, and for operating the stationary controller 6 since, without 20 the handle 23, it is impossible for any one within the car to operate the controller 21. Furthermore, the employment of the handle 23 to actuate the stationary controller 6 prevents any one from operating that controller unless the handle 23 is in his possession and also prevents the motorman from forgetting to remove the handle 23 from the stationary controller 6, as he will be unable 25 to operate his car unless he does so.
- 30 While I have shown my invention in a preferred form, it is apparent that minor modifications in the arrangement of circuits and the construction of apparatus may be made without departing from the spirit 35 thereof. I desire, therefore, to be limited only by the scope of the appended claims.
- I claim as my invention:
1. The combination with a vehicle and a motor mounted thereon for actuating said 40 vehicle, of a trolley wire having an energized portion and a normally de-energized portion, a stationary controller relatively removed from said vehicle for governing the operation of said motor by energizing 45 said normally de-energized portion.
  2. The combination with a vehicle and a motor mounted thereon for actuating said vehicle, of a conductor for energizing said motor, said conductor having a de-energized 50 section and a stationary controller relatively removed from said vehicle for controlling the energization of said de-energized section of said conductor.
  3. The combination with a vehicle having 55 a door and a motor for driving said vehicle, of a master controller for governing said motor during normal running conditions, a stationary controller relatively removed from said vehicle to govern said motor during abnormal running conditions, means for actuating said door and a detachable handle capable of actuating said means and said controllers.
  4. The combination with a vehicle and a 60 motor mounted thereon, of a trolley conduct-
- tor for energizing said motor during normal running conditions, and means comprising a normally de-energized trolley section and a controller which is independent of said vehicle for energizing said section during abnormal running conditions. 70
5. The combination with a vehicle having a door and a motor for driving said vehicle, of a master controller for governing said motor during normal running conditions, a stationary controller relatively removed from said vehicle to govern said motor during abnormal running conditions, a detachable handle for actuating said controllers, and means operated by said handle for closing 80 said door from the exterior of the vehicle, said stationary controller only being capable of operating said car upon said door occupying a predetermined position. 85
6. The combination with a vehicle and a motor mounted thereon to actuate said vehicle, of a trolley conductor for energizing said motor, a normally de-energized trolley section for stopping said motor, a controller for governing the normal operation of said motor, a braking device for stopping said vehicle, and means comprising a controller relatively removed from said vehicle for governing said motor and releasing said braking device by energizing said section. 90
7. The combination with an electric vehicle, a controller for governing the operation of said vehicle and a trolley conductor for energizing said vehicle, of a controller relatively removed from said vehicle for operating said vehicle upon the arrival thereof at a de-energized portion of said trolley conductor. 100
8. The combination with a vehicle, and a motor mounted thereon to drive said vehicle, of a trolley conductor for energizing said motor, a controller for governing the operation of said motor, an electro-pneumatic braking device for stopping said vehicle, and means comprising a controller relatively removed from said motor for governing the energization of said motor and releasing said braking device upon the arrival of said vehicle at a de-energized portion of said trolley conductor. 105
9. The combination with an electric motor, a master controller for operating said motor during normal operating conditions and an auxiliary controller for operating said motor during abnormal running conditions, of a handle which must be removed from said master controller, and applied to said auxiliary controller for actuating said motor. 110
10. The combination with a vehicle and a motor for operating said vehicle, of a master controller for governing said motor, a stationary controller relatively removed from said vehicle for governing said motor during abnormal operating conditions, and a handle capable of actuating said controller, 115 120
- 130

it being necessary to transfer said handle from one of said controllers to the other of said controllers before actuating it.

11. The combination with a vehicle having a door and a motor for driving said vehicle, of a master controller for governing the operation of said motor during normal running conditions, a stationary controller

relatively removed from said vehicle to govern said motor during abnormal running conditions, and a single device capable of actuating said door and said controllers.

In testimony whereof, I have hereunto subscribed my name this 7th day of December, 1920.

GEORGE R. IRWIN.
